ATTORNEY.

UNITED STATES PATENT OFFICE.

FREDRICK J. HARDING, JR., OF UTICA, NEW YORK, ASSIGNOR OF ONE-HALF
TO M. A. POTTER, OF SAME PLACE.

DESIGN FOR A PIPE-CLEANER.

SPECIFICATION forming part of Design No. 32,482, dated April 10, 1900.

Application filed March 1, 1900. Serial No. 7,029. Term of patent 7 years.

To all whom it may concern:

Be it known that I, FREDRICK J. HARDING, Jr., a citizen of the United States, residing at Utica, in the county of Oneida and State of New York, have invented and produced 5 a new and useful Design for a Pipe-Cleaner, of which the following is a specification, reference being had to the accompanying drawings, forming a part thereof.

Figure 1 shows a perspective view of the pipe-cleaner. Fig. 2 shows a side view. Fig. 3 shows an edge view. Fig. 4 shows a section taken on line A B of Fig. 2.

The feature of the design is the form and 15 shape of the device—that is to say, having the head consisting of four blades *a*, termi-

nating in an obtuse point, and the shank *b*, arranged on the opposite end of the head from the point, substantially as shown.

Having described my invention, what I claim as new, and desire to secure by Letters Patent, is—

The design for a pipe-cleaner, substantially as herein shown and described.

In testimony whereof I have hereunto signed my name, in the presence of two witnesses, this 20th day of February, 1900.

FREDRICK J. HARDING, JR.

Witnesses:

SARAH A. BROWN,
E. WILLARD JONES.
